UNITED STATES PATENT OFFICE.

HAROLD B. TAYLOR, OF WILKINSBURG, PENNSYLVANIA, ASSIGNEE TO WESTINGHOUSE ELECTRIC AND MANUFACTURING COMPANY, A CORPORATION OF PENNSYLVANIA.

ELECTRICAL HEATER ELEMENT AND METHOD OF MAKING THE SAME.

1,075,517.

Specification of Letters Patent.

Patented Oct. 14, 1913.

Application filed October 13, 1909. Serial No. 522,482.

To all whom it may concern:

Be it known that I, HAROLD B. TAYLOR, a citizen of the United States, and a resident of Wilkinsburg, in the county of Allegheny and State of Pennsylvania, have invented a new and useful Improvement in Electrical Heater Elements and Methods of Making the Same, of which the following is a specification.

10 My invention relates to electric resistance units and heating devices, and it has for its object to provide an improved device of this class that shall be durable in construction and efficient in operation, and a simple and 15 effective method of manufacturing the same.

Electrical devices for heating water and other fluids, and generating steam are usually so constructed that the resistance elements are operated at very high temperatures relative to those of the tubes or casing in which the elements are inclosed. For this reason, if the devices are economically constructed for operation when immersed in water or other liquid, it is usually 25 impossible to operate them under the same electric circuit conditions in the air.

According to my present invention, I utilize a resistance element comprising a strip or ribbon, of steel or other suitable conduct- 30 ing material, which is first wrapped with insulating material and is then threaded into a metal tube or pipe. When the resistance and the insulation are in position within the tube it is passed through a suitable rolling 35 press or is flattened out by some other means until the insulation which surrounds the resistance element is subjected to relatively large forces in compression. The insulation itself is preferably formed of mica or similar material which is not injured by high 40 temperatures. After the outer tube is finally flattened out, as above indicated, it may be bent, as desired, into helix, spiral, zig-zag grid or other form.

45 While my improved structure is specially adapted for water heater it is not restricted to such uses, and economical air heating devices or electrical resistance for rheostatic purposes may advantageously be constructed in the same manner, the fact that the heat generated within is almost entirely conducted away through the envelop 50 being of prime importance.

My invention is illustrated in the accompanying drawings, in which—

55 Figure 1 is a perspective view of an electric water heater for culinary purposes, and Figs. 2, 3, 4 and 5 are sectional views, on a larger scale, of the handle structure shown in outline in Fig. 1, and the heater element.

60 Referring to the Fig. 1 of the drawings, the device here illustrated comprises a heater element 1, which is bent into a zig-zag form, illustrative of any suitable design, and a handle 2, which is secured to the ends of the heater element. The supply circuit connections are established through conductors 3 and 4 that are threaded through the hollow handle 2 and are respectively connected to opposite ends of the 70 resistance strip or ribbon 5 which forms part of the heater. I prefer to utilize a resistance strip or ribbon similar to that illustrated and described in Patent #890,856, granted June 16, 1908, to the Hadaway Electric 75 Heating & Engineering Co., on an application filed by Wm. S. Hadaway, Jr., since this unit is relatively thin and flat. The form of the resistance is, however, not essential and, in some cases, it may be found de- 80 sirable to utilize a wire spiral in lieu of the aforesaid strip.

85 The heater element 1 comprises a metallic tube or envelop 6 which is first flattened into an elliptical section, the resistance ribbon or strip 5 and an insulating sheath therefor comprising two telescoping members 7 and 8. The insulated resistance is threaded into the flattened tube or envelop and, after the parts are in position, the envelop is so rolled 90 or otherwise flattened out by very high pressure that the insulating material is compressed and the space occupied by the resistance unit and the insulation is very small. The heater element thus formed may be bent 95 into any convenient shape and may be immersed in water or other fluid which it is desired to heat. The outer tube or envelop of metal serves to protect the resistance unit from injury and, since the insulating material is always under compression, a maximum amount of the heat generated in the resistance is transmitted through the walls of the tube into the surrounding medium, at any given temperature of the resistance ma- 100 terial.

105

By reason of the fact that the resistance strip or ribbon is threaded through the tube instead of being folded back on itself, both ends of the outer tube may be brought out 5 of the liquid, as illustrated in Fig. 1 of the drawings, and the usual necessity for sealing one or both ends of the tube is obviated.

The terminals of the heating device will, of course, vary according to the uses to 10 which the heater is put, and it will be understood that the handle structure illustrated is intended merely to be indicative of any suitable arrangement.

I claim as my invention:

15 1. A resistance element comprising a heat-conducting sheath having a continuous unbroken outer surface and an insulated high-resistance conductor maintained at a minimum thickness within said sheath by the 20 walls thereof.

25 2. A resistance element comprising a heat-conducting sheath having a continuous unbroken outer surface, and an insulated high-resistance conducting ribbon inclosed within said sheath and maintained at a minimum thickness by the walls thereof.

30 3. A resistance element comprising a heat-conducting sheath having a continuous unbroken outer surface and an insulated high-resistance conducting ribbon having a plu-

rality of lateral slots cut alternately in opposite edges to form a zig-zag current-conducting path therethrough and maintained under compression at a minimum thickness within said sheath.

35 4. An electric heater comprising a heat-conducting sheath, a resistance ribbon and telescoping insulating strips inclosing said ribbon, said strips and ribbon being inclosed within said sheath and maintained at a minimum thickness by the walls thereof.

5. The method of forming an electrical heater element which consists in threading an insulated conductor through a metal tube and then subjecting the assembled parts to high pressure.

6. The method of forming an electrical heater element which consists in threading an insulated conductor through a metal tube and then applying sufficient pressure to said tube to reduce the same to a minimum thickness.

In testimony whereof, I have hereunto subscribed my name this 4th day of October, 1909.

HAROLD B. TAYLOR.
